UNITED STATES PATENT OFFICE.

JOHN P. GRIFFIN, OF NEW YORK, N. Y.

ASH-TRAY.

1,342,805.

Specification of Letters Patent. Patented June 8, 1920.

Application filed May 27, 1919. Serial No. 300,020.

To all whom it may concern:

Be it known that I, JOHN P. GRIFFIN, a citizen of the United States, residing at New York city, in the county of New York and State of New York, have invented new and useful Improvements in Ash-Trays, of which the following is a specification.

This invention relates to ash trays and has for its object the provision of an ash tray particularly adapted for the use of cigarette smokers and provided with means whereby a burning cigarette stump will be extinguished when placed within the ash tray, whereby the objectionable continued burning of the stump will be prevented and whereby danger of fire and the like from carelessness will be eliminated.

An important object is the provision of an ash tray of this character which is so formed as to provide means whereby a burning stump will be smothered and which is also so constructed that the ashes upon the stump will fall into a receptacle for avoiding clogging of the smothering or extinguishing spaces.

An additional object is the provision of an ash tray of this character which will be very simple and inexpensive in manufacture, highly efficient in use, durable in service, and which may be readily disassembled for cleaning.

With the above and other objects and advantages in view, the invention consists in the details of construction to be hereinafter more fully described and claimed, and illustrated in the accompanying drawing, in which—

Figure 1 is a plan view of an ash tray constructed in accordance with my invention, a portion thereof being broken away and in section, and

Fig. 2 is a cross sectional view.

Referring more particularly to the drawing, the numeral 10 designates the base of the device which is preferably circular and dish shape, and preferably provided with a glass lining 11. The member 10 may be provided with any suitable pedestal whereby it may be supported from the floor or table, or any other article of furniture.

Disposed within the base 10, or within the lining 11 if the base is so equipped, is a

member 12 formed somewhat in the shape of a star or asterisk and which may be formed of glass, metal, or other suitable material. 55 This member 12 includes a top portion 13 and also includes a plurality of arms or points 14 between which are formed cigarette receiving passages 15 which terminate at their inner ends in holes 16, preferably oval 60 or elliptical in shape to accord with the popular shape of ready made cigarettes, and these holes open into a central opening 17 in the member 12. It will be observed that the sides of the passages 15 taper toward the 65 center of the member 12 so as to guide the burning end of a cigarette into an opening 16. It will also be observed that the passages 15 incline downwardly toward the center of the body 12. 70

In the use of the device it will be seen that in order to extinguish a smoldering cigarette stump it is merely necessary that the operator place the stump within any one of the passages 15 and press toward the center of 75 the body 12, whereby the lighted end will be engaged within the opening 16 at the end of the particular passage 15, whereby the ashes upon the end of the stump will fall off the stump and into the central opening 17, 80 it being apparent that engagement of the stump within the opening 16 will choke or smother the fire so that the cigarette will be effectually extinguished.

While the device is shown and described 85 as reduced to its simplest form, it will be readily understood that the design may be greatly elaborated upon so that the device may have an extremely attractive appearance, it being of course understood that all 90 such changes, as well as the changes in construction may be resorted to to a degree which will not depart from the scope of the subjoined claim.

Having thus described my invention, I 95 claim:—

An ash tray comprising a base receptacle having upwardly curved sides merging into the bottom thereof, a glass lining conformingly engaging within said base receptacle, 100 and a body conformingly engaged within said lining and projecting above the top of the side flanges thereof, said body being provided centrally with an opening extend-

ing to said lining and terminating short of the top of the body whereby the top of the opening will be closed, said body being somewhat stella form whereby to provide a plurality of points engaging the inner periphery of the lining, the periphery of said body between said points being spaced from the

lining to provide recesses, and said body being provided between said points with outwardly flaring recesses communicating with 10 said opening.

In testimony whereof I affix my signature.

JOHN P. GRIFFIN.
